UNITED STATES PATENT OFFICE.

JOHN EATON, OF SCHENECTADY, NEW YORK, ASSIGNOR TO GENERAL ELECTRIC COMPANY, A CORPORATION OF NEW YORK.

ELECTROMAGNETIC CIRCUIT CONTROLLER.

Application filed September 29, 1921, Serial No. 504,052. Renewed February 7, 1925.

To all whom it may concern:

Be it known that I, JOHN EATON, a subject of the King of Great Britain, residing at Schenectady, in the county of Schenectady, State of New York, have invented certain new and useful Improvements in Electromagnetic Circuit Controllers, of which the following is a specification.

My invention relates to a circuit controller which combines the feature of manual control and also the feature of automatic control to protect the controlled circuit from abnormal conditions such, for example, as an overload or a failure of voltage, although in certain of its aspects the invention is not necessarily limited to a manually controlled switch.

The present invention is a modified form of the electromagnetic circuit controller, for which I filed an application for patent on September 29, 1921, Serial No. 504,051.

In carrying the invention into effect, means is provided for closing and opening the controlled circuit at the will of the operator or in response to any predetermined condition. The same means may take the form of open and close or start and stop push buttons, although the invention is not limited to a push button switch, nor are certain features of the invention limited to their use in a manually operated switch. A switch member is under the control of the said means and also under the control of an electromagnet which may have a single winding energized responsively to the current through the switch. The electromagnet is provided with a magnetic movable member which is under the control of the magnet winding or windings, and the arrangement is such that the switch member is magnetically held thereby in an operative position as long as the conditions in the controlled circuit are abnormal, or until said manual means is operated to return the switch to its original position. In case an abnormal circuit condition occurs, such, for example, as a failure of voltage, the magnetic holding effect on the said magnetic movable member is released and the switch member is returned from the closed circuit position to the open circuit position in accordance with its bias; or in case there is an overload in the controlled circuit, the magnetic movable member is tilted to automatically open the switch and permit the

switch member to return to the open position in accordance with its bias. In the present form of the invention, which has certain advantageous features of construction and arrangement which will be pointed out particularly hereinafter, the magnetic movable member takes the form of a single armature which is biased to a position with respect to the magnetic structure of the electromagnet, to provide two air gaps in series. The arrangement is such that the armature is tilted in one direction so as to substantially close one of the said air gaps in the flux path of the electromagnet, so that the switch member is magnetically held by the armature in the closed circuit position as long as the current in the magnet winding is above a predetermined minimum value. In case the current in the magnet winding rises above a predetermined maximum value, the armature is automatically tilted in the other direction due to the magnetic pull across the second air gap, so as to open the switch and permit the armature and switch member to return to their biased positions.

For a better understanding of the invention, reference is had to the accompanying drawings in which I have shown an embodiment of my invention. Referring to the drawings, Fig. 1 is a side view of my improved switch in the open position; Fig. 2 is an end view of the same; Fig. 3 is a view showing the switch in the closed position; Fig. 4 is a view showing the relative positions of the parts when the switch is manually opened; and Fig. 5 is a very simplified diagram of a motor starting arrangement embodying the invention.

Referring to the drawings, the switch member 10 is adapted to make engagement with the stationary contact 11 to complete an electric circuit through the switch contacts and also to energize the coil 12 of the electromagnet for the switch. Switch member 10 is mechanically connected to the armature 13 and biased to the open position by means of the spring 14 which also serves as a pivotal support for the armature. The armature 13 is disposed with respect to the magnet structure of the switch to provide two air gaps 15 and 16. The air gap 15 may be termed the "closing air gap," and the air gap 16 may be termed the "opening air gap." The switch is adapted to be manually

controlled by means of the close or start push button 17 and by means of the open or stop push button 18. In such an arrangement, when the start push button 17 is depressed, the armature 13 is tilted about the spring 14 as a pivotal support to close the air gap 15, and at the same time carry the switch member 10 into engagement with the stationary contact 11 to thereby complete the electric circuit controlled by the switch, and also energize the magnet winding 12. When the current in the magnet winding 12 is above a predetermined minimum value, the armature 13 will be maintained in engagement with the upper end of the left hand leg of the U-shaped magnet structure 19 of the switch. The surface of the upper end of the left hand leg of the magnet structure 19 is angularly disposed with respect to the surface of the right hand leg of the magnet structure, so that when the switch is closed the armature 13 will be in the position shown in Fig. 3, and the air gap 16 which is open when the switch is closed, will be substantially as shown in Fig. 3. It will be observed that the switch cannot open automatically while the start button is held depressed. This feature is used to advantage when the switch is used as a starting switch for an electric motor which takes a heavy starting current but which takes a substantially lower current for normal running. Such a condition is met in the electric drive for a washing machine, for example, in which the starting torque required is very great and the normal running torque required is very materially less. If the energization of the motor is maintained during this starting interval by maintaining the start button depressed, the motor will come up to its normal operating speed and then the switch will give the automatic protection against overload and voltage failure. When the current through the magnet winding 12 rises above a predetermined maximum value, the magnetic pull across the air gap 16 will be such that the armature 13 will be caused to tilt in the opposite direction about the spring 14 as a pivot so as to thereby move the switch member 10 a short distance to the left out of engagement with the stationary contact 11 and thereby interrupt the circuit through the switch. In order for the switch to be magnetically opened when the current in the winding 12 is above the predetermined maximum value, it is not necessary that the air gap 15 be entirely opened as shown in Fig. 4, but it is merely necessary that the left hand end of the air gap 15 be opened sufficiently to permit the switch member 10 to break engagement with the stationary contact 11. Fig. 4 shows the relative positions of the parts when the switch is manually opened, and it will be under-

stood that when the switch is magnetically opened due to the current in the magnet winding rising above a predetermined value, the armature is merely tilted to a position approaching the position shown in Fig. 4, but the air gap 16 is not necessarily closed.

As thus constructed and arranged, the operation of my invention may be readily understood from a description of Fig. 5. In order to close the switch, the push button 17 is depressed, thereby connecting the motor 20 across the source of supply 21, at the same time energizing the magnet winding 12 so that the armature 13 is magnetically held in the position shown in Fig. 3. As long as the current in the magnet winding is above a predetermined minimum value, the switch will be magnetically held closed, but in case the power of the supply circuit should fail, the armature will be permitted to return to the position shown in Fig. 1, thereby interrupting the circuit through the electric motor and the magnet winding 12. The switch will remain in the open position until the operator again closes the same, or until the switch is closed in any suitable manner in response to any predetermined condition.

If while the switch is magnetically held closed, the current taken by the motor should rise above a predetermined maximum value, the magnet winding 12 will be energized to set up a flux which will produce a pull on the right hand end of the armature 13 tending to close the air gap 16, and the armature will thereby be tilted about the spring 14 a short distance so as to interrupt the circuit through the switch and permit the parts to resume their relative positions shown in Fig. 1. The motor is thus automatically disconnected from the source of supply.

When used as a push button or manually operated switch, the invention has the advantages that the switch not only serves the purposes of the ordinary start and stop push button arrangement, but it also combines the features of providing voltage failure and overload protection. It will also be observed that a single winding is necessary for magnetically holding the switch closed as long as the current in the winding is above a predetermined minimum value, and for magnetically opening the switch when the current in the magnet winding is above the predetermined maximum value.

The broad general features of an electro-magnetically controlled device which is provided with a movable controlled member biased to one position, magnetically held in a second position against its bias when the energization of the controlling electromagnet is above a predetermined minimum value, and magnetically operated away from the second position toward the first position

when the energization of the electromagnet is in excess of a predetermined maximum value, is broadly claimed in my said application, Serial No. 504,051, filed September 5 29, 1921. Furthermore, in my said former application I have broadly claimed a manually operable automatic overload and under-voltage protective switch having the broad 10 general features above set forth and arranged so as to be manually opened or closed at the will of the operator. The invention of this application is directed to a particular arrangement having the above broad general features and having, furthermore, features of simplicity of construction and arrangement whereby the broad general features are carried into effect.

In accordance with the provisions of the patent statutes, I have described the principle of operation of my invention, together 20 with the apparatus which I now consider to represent the best embodiment thereof, but I desire to have it understood that the apparatus shown is only illustrative and that 25 the invention may be carried out by other means.

What I claim as new and desire to secure by Letters Patent of the United States, is:—

1. An electric switch comprising a switch 30 member biased to the open position, a controlling electromagnet therefor comprising a magnet structure and a winding energized responsively to the current through the switch, an armature for the electromagnet connected to the switch member and biased away from the said magnet structure to provide two air gaps in series, means for tilting the said armature in one direction to close the switch and to substantially close one of 35 said air gaps, whereby the said switch member is magnetically held in the closed position when the current in the said winding is above a predetermined minimum value and the said armature is tilted in the other direction by the magnetic pull across the second air gap to open the switch when the current in the said winding is above a predetermined maximum value.

2. An electric switch comprising a switch 40 member, a controlling electromagnet therefor comprising a magnet structure and a winding energized responsively to the current through the switch, an armature for the electromagnet connected to the said switch member, means for biasing the said armature away from the said magnet structure to bias the switch member to the open position and to provide two air gaps in series between the said armature and magnet 45 structure, means for tilting the said armature in one direction about the said biasing

means as a pivotal support to close the switch and to substantially close one of said air gaps, whereby the said switch member is magnetically held in the closed position 65 when the current in the said winding is above a predetermined minimum value and the said armature is tilted in the other direction by the magnetic pull across the second air gap to open the switch when the current 70 in the said winding is above a predetermined maximum value.

3. An electric switch comprising a switch member, a controlling electromagnet therefor comprising a magnet structure and a winding energized responsively to the current through the switch, a single piece armature for the electromagnet connected to the switch member, a spring for holding the said armature away from the said magnet structure to bias the switch member to the open position and to provide an air gap between the armature and magnet structure on each side of said spring, manually operated means for tilting the said armature in one direction about the said spring as a pivotal support to close the switch and to substantially close one of the said air gaps, whereby the said switch member is magnetically held in the closed position when the current in the said winding is above a predetermined minimum value and the said armature is tilted in the other direction about the said spring to open the switch by the magnetic pull across the air gap on the other side of the said spring when the current in the said winding is above a predetermined maximum value.

4. The combination in a push button switch of a switch member, a push button for closing the switch and a push button for opening the same, a controlling electromagnet having a U-shaped magnet structure and a winding therefor in the circuit controlled by the switch, an armature for the said electromagnet connected to the said switch member and arranged to be operated by the said push buttons, the said armature disposed with respect to the said magnet structure to bridge the poles thereof and biased away therefrom to provide two air gaps in series relation, whereby the said armature is tilted to close the switch and to close one of said air gaps by the operation of the closing push button, and the switch is magnetically held in the closed position while the current in the said winding is either above a predetermined minimum value or below a predetermined maximum value.

In witness whereof, I have hereunto set 120 my hand this 28th day of September, 1921.

JOHN EATON.
